CLAIM

I claim the ornamental design for an organizer box, as shown and described.

DESCRIPTION

FIG. 1 is a first perspective view of an organizer box showing my new design;

FIG. 2 is a second perspective view thereof;

FIG. 3 is front view thereof;

FIG. 4 is rear view thereof;

FIG. 5 is a left side view thereof;

FIG. 6 is a right side view thereof;

FIG. 7 is a top plan view thereof; and,

FIG. 8 is a bottom plan view.

The broken lines depict portions of the organizer box in which the design is embodied that form no part of the claimed design.

1 Claim, 8 Drawing Sheets
